UNITED STATES PATENT OFFICE.

CHARLES D. McDONALD, OF CHICAGO, ILLINOIS, ASSIGNOR TO McDONALD MACHINE CO., OF CHICAGO, ILLINOIS, A CORPORATION OF ILLINOIS.

AUTOMATIC DIE PRESS.

Application filed January 20, 1926. Serial No. 82,395.

This invention relates to automatic die presses, and its principal object is to provide automatic mechanism for stopping the press mechanism in case of abnormal conditions in 5 the feed way for the work. The invention is in the nature of a safety device which may be applied to various types of automatic die presses, but more particularly to that type of press shown and described in 10 my prior Patents No. 1,252,278 dated January 1, 1918, and No. 1,529,031 dated March 10, 1925, to which reference is hereinafter made.

In presses of this type, metal strips are 15 fed, one at a time, from a stack of strips to a feed way, in which the strip is fed forward to the dies, in a step by step fashion, by suitable finger bar mechanism, and sometimes two strips are accidentally inserted into the 20 feed way at the same time, which results in imperfect work, and sometimes a single strip becomes buckled and jammed in the feed way. One object of the present invention is to provide automatic press stopping 25 mechanism, which is automatically set in motion when an abnormal number of strips is placed in the feed way. Inasmuch as the metal strips operated upon by the press are very thin, extreme sensitiveness is required 30 of the setting mechanism, for the press stopping mechanism, since it is desired that the press operate continuously while under normal conditions, but that when two strips are accidentally inserted into the feed way, or 35 when one strip becomes jammed therein the press stopping mechanism shall be set into operation instantaneously to thereby stop the press immediately after the abnormal condition arises. Another object is to pro- 40 vide mechanism for this purpose which is simple, inexpensive, reliable and not likely to get out of order. With these and other objects and advantages in view, this invention consists in automatic press stopping 45 mechanism, controlled by the presence of an abnormal number of strips in the feed way or by an abnormal condition of a metal strip in the feed way. The invention further consists in the several novel features hereinafter 50 fully set forth and claimed.

The invention is clearly illustrated in the accompanying drawings, in which:—

Fig. 1 is a view partly in side elevation and partly in vertical cross section of an au-

tomatic die press of common and well known 55 form, stripped of much of the operating mechanism for the purpose of clarity, and illustrating a simple embodiment of the present invention applied to the press; Fig. 2 is a view looking in the direction of the arrow 60 2 in Fig. 1 of the mechanism, forming the subject matter of this specification; Fig. 3 is a face view looking in the direction of the arrow 3 in Fig. 1, and partly in section, of the finger bar mechanism, its actuating mecha- 65 nism and certain members of the press stopping mechanism forming the subject matter of this specification; Fig. 4 is a detail section taken on the line 4—4 of Fig. 1; Fig. 5 is a detail section through an air valve used in 70 the press stopping mechanism; Fig. 6 is an enlarged detail cross section showing the feed way of the press and certain members of the press stopping mechanism; Fig. 7 is a view partly in side elevation and partly in 75 section of a certain clutch throwing arm, an arm actuating rod and the connections therebetween, Fig. 8 is an elevation of the parts seen in Fig. 7 looking in the direction of the arrow 8, and Fig. 9 is a view partly in section of a slightly modified form of connecting device between the clutch throwing arm and arm actuating rod.

Referring to said drawings, which illustrate a simple embodiment of the invention applied to an automatic die press of the type illustrated in the above mentioned patents, the reference character 10 designates the press body, 11 the table for holding the metal strips, and 13 the feed way into which metal strips are inserted by suitable strip inserters (not shown). The feed way has a stationary side wall 16, 16¹ and a movable side wall 18, the latter being pivotally secured to the base portion 22 of the table 11 (see Fig. 6) by arms 19, whereby the movable side wall 18 may be swung back to expose the feed way for any purpose. Projecting into the feed way 13 are the fingers 17 of the finger bar mechanism and the bar 17 of said finger bar mechanism is reciprocated by mechanism so as to feed the metal strip (with which the fingers engage in succession) in a step by step fashion toward the die mechanism (not shown). In the form illustrated, a slide block 36, sliding in guide ways in the table base 22, is connected to a connecting rod 35 by a connecting pin 44

secured in a lug 42 of the slide block and held in a stirrup portion 37 of the connecting rod 35 by a spring pressed pin 45 which is contained in a socketed lug 35^a, formed on the connecting rod 35, and bears against the connecting pin, 44. The stirrup 37 has an offset portion 37^a at one end, in which the connecting pin 44 is normally held by the spring pressed pin 45. The arrangement is such that under normal conditions, when the connecting rod 35 is reciprocated, it reciprocates the slideblock 36 and therewith the finger bar 17 and finger bar mechanism. Adjustable stop members 50, 51 are provided, one in front of each end of the slide block, which act as stops for limiting any lengthwise movement of the slide block independent of the connecting rod. The connecting rod is reciprocated by the usual actuating mechanism, as is well understood, as well as by reference to my prior patents above referred to.

As in the presses of my prior patents there is a crank shaft 9 for actuating the dies, and manually operated press starting and stopping mechanism, consisting briefly of clutch mechanism, and brake mechanism, and a hand lever 72 fulcrumed on one side of the press body and connected to the clutch and brake mechanism by link mechanism as in my prior patents.

With the exception of the exact form of loose connection between the connecting rod and slide block above described, the mechanism described conforms generally to that illustrated and described in my prior patents above referred to.

The mechanism for automatically stopping the press in case of an abnormal condition in the feed way 13 will now be described.

Projecting into the feed way is the setting element of said mechanism. It is here shown as comprising a pin 60 having one end projecting into the feed way 13 and standing in the path of movement of the thin metal strips as they are being inserted into the feed way (see Fig. 6). Said pin 60 is slidably mounted in a bearing bracket 61 supported upon the table portion 22, and engages with one arm 62 of a lever 63 which is shown as fulcrumed upon the bracket 61 to swing in a plane transversely to the feed way. The other arm 64 of the lever 63 is considerably longer than the arm 62, whereby any slight movement of the shorter arm will be multiplied many times in the longer arm 64. This is because the movement imparted to the pin 60 by the thin strip of metal is very slight, and a longer stroke of the long arm is thereby obtained, which in many forms of operating mechanism is required. In its present form the lever 63 is employed to open an air valve of a vacuum line, or an air pressure line, which leads to the cylinder of a suitably constructed connecting device

which operates to connect a continuously reciprocating rod with a clutch throwing arm whenever the lever 63 is actuated.

Referring now to Figs. 1 and 2, a vacuum pipe 65 leads from a vacuum pump (not shown), and in case the die press is equipped with a vacuum pump, the pipe may lead therefrom, otherwise it may lead from any other suitable source. In the vacuum pipe 65 is interposed an air valve 66 which is normally closed. The valve 66 is placed in a position in which its valve stem 67 will stand in front of the end of the long arm 64 of the lever 63, in position to be engaged thereby whenever the lever 63 is moved by the pin 60. Whenever the lever 63 is moved by the pin 60, it actuates the valve stem and unseats the valve, thereby permitting the vacuum (present in the vacuum pipe 65 up to the valve) to extend to the clutch throwing arm connecting device and thereby setting it in active position for actuating the clutch throwing arm. A vacuum pipe 68 connected to one side of the air valve 66 leads to said connecting device. To afford adjustment between the lever 63 and valve stem 67, an adjustment stud 69 (see Fig. 6) is threadedly secured in the end of the arm 64 of the lever 63. This adjustment stud can be adjusted nicely so as to make the action of the lever 63 very sensitive. It is to be understood that the parts are so adjusted that when one metal strip at a time is inserted into the feed way, the lever 63 remains inactive and the air valve remains closed.

When, however, two or more strips are fed into the feed way as seen in Fig. 6, the pin 60 is thereby moved endwise to the left, as viewed in Fig. 6, the long arm of the lever 63 thereby swung to the right, the valve stem depressed and the valve opened. Opening the vacuum line to the connecting device for the clutch throwing arm causes a detent to become interposed between the clutch throwing arm and a continuously moving arm actuating mechanism, whereby said arm is actuated in a direction to operate the clutch mechanism and stop the press mechanism.

The clutch throwing arm 70, is secured upon one end of a rock shaft 71, which in the form of the invention illustrated, extends through the press body and is secured, at its other end, to the clutch throwing lever 72. A continuously moving element, as for instance a reciprocating rod 73 is provided for actuating the clutch throwing arm 70 whenever an abnormal condition arises in the feed way, said rod being normally disengaged from the clutch throwing arm and reciprocating freely with respect thereto. For reciprocating the rod 73 I provide a cam block 74 on the crank shaft 9 of the press, which engages with an arm 75 of a bell crank lever 76, or a roller thereon, the other end of the lever being connected to the

rod 73. Obviously, engagement of the rotating cam or cams of the cam block with the arm 75 of the bell crank lever 76 causes reciprocation of the rod 73. Other equivalent means may be substituted for the rod reciprocating means described, as is well understood and I do not wish to be understood as intending to limit myself to the exact form of means shown.

The rod 73 extends down to the clutch throwing arm 70 and passes loosely through a block 78 which is secured to and fulcrumed between the forks 79 of the clutch throwing arm 70. On the lower end of the rod 73 is a shoulder or stop member, 80, here shown in the form of a block secured to the rod 73 by a nut 81, threaded on the rod below the shoulder 80, and a set screw 82 threaded in the block 80 and bearing against the rod.

Pivottally supported in a hollow space in the block 78 is a detent 83, normally held out of the path of movement of the shoulder 80, by a spring or otherwise, but arranged to be moved into the path of movement of said shoulder, for engagement therewith, whenever an abnormal condition arises in the feed way. In the form of means shown for actuating the detent 83, a vacuum cylinder 84 is employed, which cylinder may be formed in the block 78, if desired, and in said cylinder is a plunger 85 which is connected to the detent by a stem 86. The detent and cylinder are shown as extending in a direction generally parallel with the rod 73, and the detent is shown as formed with an arm 87, arranged at right angles to the main body of the detent, and engaging with the stem 86 of the plunger 85. Downward movement of the plunger in the cylinder acts to swing the lower end of the detent to the right (as viewed in Fig. 7) in position for engagement with the shoulder 80, on its up stroke. The vacuum pipe 68 leads from the vacuum cylinder 84 to the air valve 66, as has been heretofore explained. When the air valve is opened, a partial vacuum is created in the cylinder 84, the plunger 85 is drawn down therein, the detent 83 swung into position for engagement with the shoulder 80 on the rod 73, which on its next up stroke, engages the detent, lifts it and therewith the block 78, and swings the clutch throwing arm 70 upward, which turns the rock shaft 71 and swings down the starting lever 72, thereby actuating the clutch and brake mechanism and stopping the press. As soon as the air valve 66 is closed, the vacuum is shut off, the detent moved to normal position and the hand lever is again free to be manipulated to start the press.

Whenever a jam occurs in the feed way, movement of the finger bar 17 is arrested, and because of the loose connections 37, 44, 45, between the slide block 36 and connect-

ing rod 35, the press mechanism is free to operate until stopped, and ordinarily the connecting rod 35 was therefore reciprocated idly until the press was stopped, the jam removed and the press again started. In accordance with one phase of the present invention, whenever a jam occurs, and the pin 44 is thereby forced out of the inclined part of the slot in the stirrup 37, the automatic press stopping mechanism is set into action, and the press stopped. The means for accomplishing this result will now be described.

Referring to Figs. 1 to 4, inclusive, it will be seen that the stirrup 37 has a slide block 90, bolted or otherwise secured to it, and which extends lengthwise of the stirrup. Under normal conditions, said slide block reciprocates idly, but whenever the coupling pin 44 is forced out of the inclined part of the slot of the stirrup, the stirrup and slide block are thereby moved laterally of the coupling pin 44, thereby bringing the slide block into a path of movement, wherein it actuates valve mechanism for unseating the valve of an air valve in the vacuum line running to the vacuum cylinder 84, and thereby setting in motion the automatic press stopping mechanism. In its present form, said means comprises a swinging arm or plate 91 fulcrumed on a bracket 92, secured to the table portion 22, and lying contiguous with, but out of the normal path of movement taken by the slide block 90, the arrangement of the parts being such that when the coupling pin 44 is forced out of the inclined end of the slot of the stirrup and the latter thereby moved sidewise, the slide block 90 swings back the arm or plate 91, and opens an air valve 93 of the vacuum mechanism, as will be presently explained.

Leading from the vacuum line 65 is a branch pipe 94 on which is the air valve 93, said air valve being placed in position where its valve stem will be actuated by the arm or plate 91 or an adjustment stud 95 thereof. A branch pipe 96 leads from the air valve 93 to the pipe 68, to which it is connected by suitable fittings.

It will be observed from an inspection of Fig. 2, that the vacuum pump is connected to one side of the air valves 66, 93, by the pipes, 65, 94, and that said valves are normally held in closed position. It will also be seen that the other side of said valves 66, 93 are connected to the vacuum cylinder 84 by the pipes 68, 96. If either air valve is opened, communication is established between the vacuum pump and vacuum cylinder 84, through the air valve which was opened.

From the above description it is apparent that when two or more thicknesses of strips are placed at the same time in the feed way, the air valve 66 is opened, and the au-

tomatic arm actuating mechanism for the clutch throwing arm is set in motion, the arm is raised and the press stopped. It will also be apparent that if a jam occurs in the feed way causing the finger bar to be blocked, that the connection between the finger bar and its actuating mechanism is automatically broken, the air valve 93 opened and the press stopped through the instrumentality of the automatic press stopping mechanism. When the excess strip or buckled strip is removed from the feed way, the press is started in the usual way by lifting up on the starting lever.

In the modified form shown in Fig. 9 of the connecting device between the clutch throwing arm and arm actuating rod, a compressed air cylinder 84^a is shown, in which is a plunger 85^a connected to the detent 83^a by a stem 86^a. A compressed air pipe 68^a leads from a suitable air compressor, not shown, to the compressed air cylinder 84^a and supplies compressed air to said cylinder. The other parts of the device are substantially like those shown in the preferred form. It is obvious that when either of the valves, which in this case are interposed in the pipe 68^a between the air compressor and the compressed air cylinder 84^a, is opened the plunger 85^a will be moved in a direction to throw the detent 83^a into engagement with the shoulder 80 on the clutch actuating rod 73 on its next up stroke.

More or less variation of the exact details of construction is possible without departing from the spirit of this invention; I desire, therefore, not to limit myself to the exact form of the construction shown and described, but intend, in the following claims, to point out all of the invention disclosed herein.

I claim as new, and desire to secure by Letters Patent:

1. In an automatic die press, the combination with a feed way for the work, finger bar mechanism, associated therewith, finger bar actuating mechanism, and clutch throwing mechanism for starting and stopping the press, of a normally inactive clutch throwing arm, a block having a vacuum cylinder therein and carried by said arm, and having a vacuum plunger therein, a reciprocating arm actuating rod guided in said block, and having a shoulder thereon, a detent mounted on said block for engagement with said shoulder on the rod, and operatively connected to said vacuum plunger, a vacuum pipe leading to said vacuum cylinder, a normally closed air valve in said vacuum pipe, and sheet actuated emergency mechanism arranged to open said valve.

2. In an automatic die press, the combination with a feed way for the work, finger bar mechanism, associated therewith, finger bar actuating mechanism, and clutch throw-

ing mechanism for starting and stopping the press, of a normally inactive clutch throwing arm, a block having a vacuum cylinder therein and carried by said arm, and having a vacuum plunger therein, a reciprocating arm actuating rod guided in said block, and having a shoulder thereon, a detent mounted on said block for engagement with said shoulder on the rod, and operatively connected to said vacuum plunger, a vacuum pipe leading to said vacuum cylinder, a strip engaging element extending into said feed way, an air valve in said vacuum pipe, and valve operating connections between said strip engaging element and valve.

3. In an automatic die press, the combination with a continuously moving press element, a feed way for the work, sheet feeding mechanism, and clutch throwing mechanism for starting and stopping the press, of normally inactive emergency press stopping mechanism, comprising an emergency press stopping element directly operated by said continuously moving press element and arranged for operative connection with said clutch throwing mechanism, but normally unconnected therewith, a normally inactive movable member, made operative solely under the influence of an abnormal condition in the feed way, and operative connections between said normally inactive movable member, and said emergency press stopping element for operatively connecting the latter element with said clutch throwing mechanism.

4. In an automatic die press, the combination with a continuously moving press element, a feed way for the work, sheet feeding mechanism, and clutch throwing mechanism for starting and stopping the press, of normally inactive emergency press stopping mechanism, comprising an emergency press stopping element directly operated by said continuously moving press element and arranged for operative connection with said clutch throwing mechanism, but normally unconnected therewith, a normally inactive movable member, made operative solely under the influence of an abnormal condition in the feed way, pneumatic means for operatively connecting said emergency press stopping element with said clutch throwing mechanism, said pneumatic means including an air line, and an air valve in said air line and actuated by said normally inactive movable member.

5. In an automatic die press, the combination with a feed way for the work, sheet feeding mechanism, embodying two connectible and disconnectible members, one of which is a driver and one a driven element, said driver capable of movement independently of the driven member, and having a normally inactive actuating member which is made active whenever the driver is dis-

connected from the driven element, an emergency clutch actuating member, normally inactive mechanism for actuating said emergency clutch actuating member, and means for setting into action said normally inactive mechanism, operated by said actuating member of the connectible and disconnectible driving and driven members.

6. In an automatic die press, the combination with a feed way for the work, sheet feeding mechanism, embodying two connectible and disconnectible members, one of which is a driver and one a driven element, said driver capable of movement independent of the driven member, and having a normally inactive valve actuating member which is made active whenever the driver is disconnected from the driven element, an emergency clutch actuating member, normally inactive mechanism for actuating said emergency clutch actuating member, a vacuum line, an air valve therein actuated by said actuating member, and a vacuum actuated setting member on said vacuum line operating to set into action said normally inactive mechanism for actuating the clutch actuating member.

7. In an automatic die press, the combination with a feed way for the work, sheet feeding mechanism, embodying two connectible and disconnectible members, one of which is a driver and one a driven element, said driver capable of movement independent of the driven member, and having a normally inactive valve actuating member which is made active whenever said driver is disconnected from the driven element, power mechanism, starting and stopping mechanism therefor, an emergency power disconnecting member, normally inactive mecha-

nism for actuating said emergency power disconnecting member, including a vacuum operated arm connecting mechanism, a vacuum pipe leading to said arm connecting mechanism, and a valve in said vacuum pipe arranged to be actuated by said valve actuating member.

8. In an automatic die press, the combination with a feed way for the work, sheet feeding mechanism including a finger bar and a connecting rod having a stirrup and pin connection with the finger bar, said stirrup being capable of lateral movement relative to said pin connection whenever disconnected from said pin, an air valve arranged to be actuated by said stirrup whenever it is disconnected from said pin, a vacuum line in which said air valve is interposed, and emergency clutch throwing mechanism having a vacuum operated element on said vacuum line, for setting into action said emergency clutch throwing mechanism.

9. In an automatic die press, the combination with a feed way for the work, sheet feeding mechanism including a finger bar and a connecting rod having a stirrup and a pin connection with the finger bar, said stirrup having an inclined slot for affording lateral movement relative to said pin connection whenever disconnected from said pin, a slide block on said stirrup, an air valve arranged to be actuated by said slide block whenever the stirrup is disconnected from said pin, a vacuum line in which said air valve is interposed, and emergency clutch throwing mechanism having a vacuum operated element on said vacuum line, for setting into action said emergency clutch throwing mechanism.

CHARLES D. McDONALD.
